UNITED STATES PATENT OFFICE

2,632,434

COOKING RANGE STRUCTURE

George C. Pearce, Dayton, Ohio, assignor to General Motors Corporation, Dayton, Ohio, a corporation of Delaware

Application September 1, 1945, Serial No. 613,982

5 Claims. (Cl. 126—1)

1

This application relates to domestic appliance and more particularly to ranges.

An object of this invention is to provide a range in which a substantially rectangular box-like skeleton frame is provided, to which side panels, a cooking top, an oven liner, an oven door, and other parts may be attached to form the completed range with the side panels supporting the skeleton frame in the upper portion of the range.

Further objects and advantages of the present invention will be apparent from the following description, reference being had to the accompanying drawings, wherein a preferred form of the present invention is clearly shown.

In the drawings:

Fig. 1 is a front view, in perspective, showing the completed range;

Fig. 2 is a perspective front view of a portion of Fig. 1, with the two doors of the range withdrawn therefrom and showing the range oven door in open position;

Fig. 3 is an exploded view, in perspective, of a large number of parts for the range;

Fig. 4 is a view of the rear panel of the box-like skeleton frame looking toward the inside surface thereof;

Fig. 5 is a view of the right-hand edge of the rear panel shown in Fig. 4;

Fig. 6 is an inside elevational view of the left-hand side panel of the range;

Fig. 7 is a view of the right-hand edge of the side panel disclosed in Fig. 6; and

Fig. 8 is a view of the left-hand edge of the side panel disclosed in Fig. 6.

The range shown in Fig. 1 may comprise a main body consisting of a plurality of porcelain enameled outer metal pans or panels to be hereinafter described in detail. The main body may be assembled around or constructed on a skeleton structure comprising a rectangular box-like frame 11 (see Fig. 3) to which portions of the main body may be attached. Thus a left hand side panel 12 and a right hand side panel 13 may be attached to sides of the frame 11, and may extend below the frame 11 a substantial distance to form the support for the range, or to surround the support for the range. The top panel 14 may be placed over the frame 11 to form the cooking top. An oven liner 15, which is flanged at 16 (see Fig. 3) may be telescoped into the opening 17 of the frame 11. If desired, a drawer 18 may be telescoped into the opening 19 of the frame 11, and may carry an ornamental front plate 20. An oven door 21 may be hinged on

5 the frame 11 in any suitable manner such for example as shown and described in my Patent No. 2,569,775, dated October 2, 1951, which is a continuation-in-part of the present application, to close the open front end of liner 15. A lower drawer 22 may slide on the channels 23, and may be provided with an ornamental front 24. A foot plate 25 may be attached to the two side panels 12 and 13 and may tie them together to form a rigid structure.

2

Details of the rectangular box-like frame

The frame 11 preferably is made of channel or angle iron structure, and preferably has a ground coat of enamel applied thereto. Channel or angle iron members are welded together substantially as indicated in Fig. 3 of the drawings. A partition 26 extends from the front to the rear, to retain insulation around the oven liner 15. The front of the frame 11 includes upright channels 27, 28 and 29, a horizontal lower channel 30, an upper right hand channel 31 and a left hand upper channel 32. The right hand side of the frame 11 may include a lower channel 140 and an upper angle 33. The left hand side of frame 11 may include a lower channel and upper angle members similar to 140 and 33 respectively at the right-hand side thereof. The frame 11 includes a rear panel 35 which forms a back wall of the frame and consequently the back wall of the range. Another channel 140 may extend from the front to the back of skeleton frame 11 adjacent the lower edge of panel 26. All of these members are preferably firmly welded together to form a strong box-like rectangular frame structure.

Double channel members 36 are secured inside of the frame 11, to the rear of opening 19, which are adapted to support a combined drip plate and the broiler pan 37 (see Fig. 2) while not in use. Channel members 38 are also secured to the rear of opening 19 to support the drawer 18, which is provided with suitable flanges 39 along its upper edge to fit into the channels 38.

Details of the side panels

The side panels 12 and 13 are preferably provided with upper and lower flanges 40, 41 and front and rear flanges 42 and 43. Suitable openings 44 are provided in these flanges so that bolts or screws may pass therethrough for attachment to the frame 11. Brackets 45 are bolted to the front flanges 42, and gussets 46 are bolted to the flanges 43 (see Fig. 3). A channel

23 extends from the bracket 45 to the gusset 46 at each side of the range (see Figs. 2 and 3). The drawer 22 slides on the channels 23 through the medium of upper flanges 48 at the top of drawer 22. The gussets 46 are secured to the rear panel 35 to brace the rear of the panels 12 and 13. The foot plate 25 is bolted to the lower ends of the flanges 42 of the panels 12 and 13 to join the two panels rigidly at the front.

The top panel 14 is secured in place by any suitable means such as gussets through which conventional bolts or screws may pass and be secured to the box frame 11. The front 52 of top 14 of the range is provided with a rearwardly extending flange. This flange may be slid under the heads of bolts, which are secured to the front 31 of frame 11 through the medium of suitable brackets or the like, before the top 14 is secured at the rear of the frame. This prevents the top 14 from being lifted upwardly after it is secured in place.

The top 14 may support a plurality of top heaters 60 and/or a top cooker 61 (see Figs. 1 and 2). These may be of any well known construction, which are adapted to be supported by the top 14, such as disclosed in McCormick Patent 2,320,041, granted May 25, 1943.

The front upper channel or bar 32 is provided with an opening 62 (see Fig. 3) to accommodate switch means for the heaters 60 and 61. These switch means may be secured to a channel suitably mounted in opening 62 and have their knob stems extending through openings in the channel. The stems of these switch means also extend through openings 68 (see Fig. 2) in the top 14, where suitable knobs 69 (see Fig. 1) are secured in front of the top 14 for manipulation by the user. A closure panel (not shown) may be secured to the rear of member 32, which boxes off the switches and prevents the shorting or injury thereto. The wiring to the heaters 60 and 61 may pass through an opening provided in such closure panel. Top 14 of the range may be provided with an upstanding back portion into or upon which may be mounted fluorescent light 104, an electric clock 122, an oven heater control handle 98, an automatic oven heater timer clock 121 and an oven vent opening 158 (see Fig. 1) as is usual or conventional in the art.

The oven liner 15 preferably is made in two or more sections welded together. The side walls 125 of liner 15 have inward corrugations 126 which form grooves on the outside of the liner and shelf ridges 126a on the inside of the liner (see Figs. 2 and 3). The sheet of metal which forms the side walls 125 of liner 15 is bent to form a square hollow tube with flanges 16 welded or formed thereon at one end and no flanges at the other end. A metal cup 127, rectangular in cross-section, is telescoped over the rear end of this tube, and is welded thereto. Several pockets 128 are thus formed where the grooves 126 meet the edge of the cup 127. Two or more J-shaped bolts 129 may be hooked over the edge of the cup 127, at 128, and these bolts 129 may extend through openings 131 (see Fig. 3) provided in the rear plate or panel 35. A suitable nut and washer placed over the bolts 129 may be drawn tightly against the rear panel 35. In this manner the flange 16 on liner 15 is drawn up against the inner edges of walls of the opening 17. Thus the oven liner 15 is positioned in the skeleton frame structure with its open end portion secured thereto about the opening 17 therein and with its rear portion supported

by the bolts 129 from the back wall or panel 35 thereof.

The construction and operation of the oven door 21 may be of any conventional design; but 5 preferably is substantially as shown and described in Figs. 33 through 36 of my patent hereinabove identified.

In assembling the range herein disclosed the members of the skeleton frame or box 11 are first welded together. The panels 12 and 13 are attached to the box 11. The foot plate 25 is secured to the panels 12 and 13 to lock the portions thereof depending below box or frame 11 to one another. The liner 15 is then assembled to the box or frame 11. Thereafter the top panel 14 is mounted upon the skeleton frame 11 and the drawers 18 and 22 are slid in place upon their respective tracks or supports 38 and 23.

While the form of embodiment of the invention as herein disclosed, constitutes a preferred form, it is to be understood that other forms might be adopted, as may come within the scope of the claims which follow.

What is claimed is as follows:

1. In combination, a cooking range having a unitary self supporting skeleton structure, said skeleton structure comprising upright members forming vertically extending corners at the front of said range, a plurality of substantially horizontal members disposed substantially at right angles to said upright members and a rear panel, said upright members, said rear panel and said horizontal members being rigidly joined together with said rear panel forming a back wall of said skeleton structure, said rear panel having an edge portion thereof along each of its upright sides flanged and forming vertically extending rear corners on said structure, separate side panels for said range each having their upright edges flanged, said side panels extending around the front and rear vertical corners of said structure with their flanged edges secured to said upright members and said back wall thereof respectively, a separate panel upon said structure forming the top of said range, said structure having an opening in the front thereof, an oven liner within said range, said liner having an open end, said liner being positioned in said structure with its open end portion secured thereto about the opening in the front thereof and its rear portion supported from said back wall, an oven door hinged to said structure in front of said liner for closing its open end, and said side panels depending below said structure and forming the sole means of supporting the structure in the upper portion of said range.

2. The combination set forth in claim 1 wherein in guide means is carried by and extends along the depending portion of each of said side panels, and a drawer is movably mounted upon the opposed guide means below said structure.

3. The combination set forth in claim 1 wherein in rigid means is secured to a lower portion of the rear vertical flange of each of said side panels and is attached to said back wall for bracing the depending portions of said side panels.

4. The combination set forth in claim 1 wherein in a plate extends across the front of said range below and in spaced relation to said structure and has its ends secured to said side panels for locking the depending portions of the panels to one another, guide means is carried by and extends along the depending portion of each of said panels, and a drawer is movably mounted upon the opposed

guide means in the space between said structure and said plate.

5. In combination, a cooking range having a unitary self supporting skeleton structure, said skeleton structure comprising upright means forming vertically extending corners at the front of said range, horizontal means disposed substantially at right angles to said upright means and a rear panel, said upright means, said rear panel and said horizontal means being rigidly joined together with said rear panel forming a back wall of said skeleton structure, separate side panels for said range each having their upright edges flanged, said side panels extending around the front and rear vertical corners of said structure with their flanged edges secured to said upright means and said back wall thereof respectively, a separate panel upon said structure forming the top of said range, said structure having an opening in the front thereof, an oven liner within said range, said liner having an open end, said liner being positioned in said structure with its open end portion secured thereto about the opening in the front thereof and its rear portion supported from said back wall, an oven door in front of said liner for closing its open end, and said side panels depending below said structure and forming the

sole means of supporting the structure in the upper portion of said range.

GEORGE C. PEARCE.
